UNITED STATES PATENT OFFICE.

FRED W. GUNN, OF BOSTON, MASSACHUSETTS.

TOOL FOR APPLYING WIRE CLAMPS TO HOSE COUPLINGS.

Application filed January 21, 1924. Serial No. 687,559.

To all whom it may concern:

Be it known that I, FRED W. GUNN, a citizen of the United States, and resident of Boston, in the county of Suffolk and State of Massachusetts, have invented certain new and useful Improvements in Tools for Applying Wire Clamps to Hose Couplings, of which the following is a specification.

My invention relates generally to improvements in tools for securing clamping or binding wires on a hose or like article, more particularly to a tool which is particularly well adapted for use in applying a wire clamp having the construction disclosed in my prior application for Letters Patent of the United States, Serial #661,419, filed September 7, 1923, and it consists in the combinations, constructions and arrangements herein described and claimed.

An object of the invention is to provide a tool of the character described which is adapted to be easily and conveniently manipulated to effect twisting together of the end portions of the clamping or binding wire against a length of hose or like article which is encircled by the binding or clamping wire and to then cause breaking off of the end portions of the clamping wire at the outer ends of the twisted together portions thereof.

A further object of the invention is to provide a tool of the character described which affords facilities for twisting together end portions of a clamping wire so that the end portions of the clamping wire will be broken off at the outer end of the twisted together portion and also at the outer end of the tool, thus facilitating removal of the broken off end portions of the wire from the tool.

Other objects and advantages will be apparent from the following description, taken in conjunction with the accompanying drawings, in which—

Figure 1 is a perspective view showing a tool embodying the present invention,

Figure 2 is a longitudinal section through the tool,

Figure 3 also is a longitudinal section through the tool, the view being taken substantially at right angles to Figure 2,

Figure 4 is a relatively enlarged perspective view showing tightening means which is comprised in the device.

A tool embodying the invention in the form now preferred by me comprises an

elongated body 1 which preferably is enlarged adjacent one end thereof to provide a handle portion 2 which is adapted to be firmly gripped in the hand of the user. The handle portion of the body is apertured as indicated at 3 for the sake of lightness.

The body 1 is provided at its other end with a head 4 which is preferably circular in cross sectional contour and tapers toward its extremity, the end wall 5 of the head lying in a plane which extends at right angles to the longitudinal axis of the body. The head 4 extends laterally of one side of the body 1 and is provided with a bore 6 which extends longitudinally therethrough in parallel relation to the longitudinal axis of the body and at one side of the aforesaid side wall of the body.

The longitudinal axis of the body 1 is intersected by a transverse opening 7 which is formed in the body 1 a short distance rearwardly of the juncture of the body and head 4. A tightening pin 8 extends through the opening 7 and has an end portion 10 thereof protruding from one end of the opening 7 and located directly at the rear of the bore 6 in the head 4, the other end portion of the pin 8 protruding from the opposite end of the opening 7 and being enlarged and fashioned to be non-circular in cross sectional contour as indicated at 11 for a purpose to be hereinafter described. The tightening pin 8 is freely rotatable but is held against axial movement relatively to the body 1 by retaining pins 12 which are carried by the body and are partially received in a circumferentially extending groove 13 in the outer wall of the pin 8.

The tightening pin 8 has a diametrically extending slot 14 formed in the first mentioned end thereof. This slot preferably extends in the pin to the plane of the adjacent face of the body 1.

An anchor pin 15 is secured adjacent to one end in a transverse opening 16 in the body 1 and extends laterally of the body 1 in spaced parallel relation to the tightening pin 8, being located rearwardly of the latter and at a slightly lower level.

The bore 6 is intersected adjacent its rearward end by a pair of vertically spaced parallel bores 17 which extend transversely through the head 5 and which have the respective axes thereof located in planes equidistant from the axis of the bore 6. Each transverse bore 17 receives a spacing pin 18,

the two pins 18 being spaced apart a distance which is just sufficiently greater than the diameter of the wire of which a wire clamp is formed to permit the ends of the wire clamp to be inserted through the bore 6 between the guide pins, the distance between the two guide pins not being sufficiently great to permit the end portions of the clamp to be twisted together between the guide pins or rearwardly thereof.

From the foregoing description of the various parts of the device, the operation thereof may be readily understood. The free ends of the wire clamp which has been arranged in encircling relation to a length of hose or like article are extended through the bore 6 between the guide pins 18 in side by side relation and then through the slot 14 in the tightening pin 10 and finally are secured to the anchor pin 15 by having the extreme end portions thereof twisted about the anchor pin. At this time, the end of the head 5 will be in position to clamp or press the wire clamp against the hose or other article which is encircled by such wire clamp. As stated, the enlarged end portion 11 of the tightening pin 10 is non-circular in cross sectional contour and has a sufficient number of faces to adapt it to be gripped by a suitable wrench or turning tool, not shown. The tightening pin 8 is turned by means of a wrench such as that mentioned until the wire clamp has been drawn tight. The body 1 then is turned about its longitudinal axis, thus effecting the twisting of the end portions of the wire clamp, whereby such clamp will be secured in place on a hose or like article. Since the guide pins 18 prevent the twisting together of the end portions of the wire clamp between such guide pins or rearwardly thereof, it will be manifest that continued turning of the body 1 about its longitudinal axis will cause the end portions of the wire clamp to be broken off between the guide pins 18. The broken off end of the wire clamp then may be removed readily from the tool.

Obviously, my invention is susceptible of embodiment in forms other than that illustrated in the accompanying drawing and I therefore consider as my own all such modifications and adaptations of the form of

the device herein described as may fairly fall within the scope of the appended claims.

I claim:

1. A tool of the character described comprising an elongated body having a head at one end thereof, said head having a bore extending longitudinally therethrough, a pair of spaced apart guide members extending transversely through said bore, and a rotatable tightening pin carried by said body, said tightening pin having a slotted end portion extending at right angles to the direction of length of said bore and being located at the rear of said head.

2. A tool of the character described comprising an elongated body having a head at one end thereof, said head having a bore extending longitudinally therethrough, a pair of spaced apart guide members extending transversely through said bore, and a rotatable tightening pin carried by said body, said tightening pin having a slotted end portion extending at right angles to the direction of length of said bore and being located at the rear of said head, and an anchor pin carried by said body, said anchor pin being located rearwardly of said tightening pin and having a portion thereof disposed in spaced parallel relation to the slotted portion of said tightening pin.

3. A tool of the character described comprising an elongated body having a head at one end thereof, said head having a bore extending longitudinally therethrough, said bore being located laterally of the side of said body, a pair of spaced apart guide pins extending transversely through said bore adjacent to the rearward end of the latter, one of said guide pins being disposed above the other, a rotatable tightening pin carried by said body, said tightening pin being located rearwardly of said head and having a slotted end portion extending laterally of said side of the body and at the rear of said bore, and an anchor pin carried by said body, said anchor pin being disposed rearwardly of said tightening pin and having a portion extending laterally of the body in spaced parallel relation to said tightening pin.

FRED W. GUNN.
